Phillips, Muller & Fisch

UNITED STATES PATENT OFFICE.

JOHN H. RIGBY, OF BEVERLY, MASSACHUSETTS, ASSIGNOR, BY MESNE ASSIGNMENTS,
TO UNITED SHOE MACHINERY CORPORATION, OF PATERSON, NEW JERSEY, A COR-
PORATION OF NEW JERSEY.

MACHINE FOR OPERATING UPON SHOE-SOLES.

1,351,065.

Specification of Letters Patent. Patented Aug. 31, 1920.

Application filed February 10, 1916. Serial No. 77,395.

To all whom it may concern:

Be it known that I, JOHN H. RIGBY, a citizen of the United States, residing at Beverly, in the county of Essex and State of Massachusetts, have invented certain new and useful Improvements in Machines for Operating upon Shoe-Soles; and I do hereby declare the following to be a full, clear, and exact description of the invention, such 10 as will enable others skilled in the art to which it appertains to make and use the same.

This invention relates to machines for operating upon the marginal portions of shoe soles, and more particularly to a machine for burnishing ornamental impressions or indentations upon shoe soles. In ornamenting the marginal portion of a shoe sole, it is the common practice to preliminarily 15 place indentations or impressions on the sole, then ink them, and then burnish the inked impressions or indentations. The tool used for burnishing the indentations is generally heated by a gas flame which is directed upon the tool. Many of the inks used upon the soles are inflammable, and when they are brought into contact with the flame by the burnishing tool, a soot or smudge is formed which often discolors the 20 sole, and is very disagreeable to the operative. The action of the naked flame upon a part of the tool in heating it also tends to draw the temper from the tool and render it unfit for use.

35 The primary object of the present invention is to provide a heating device for the tool of an indenting or impression burnishing machine which will efficiently heat the burnishing tool and overcome the above ob-

40 jections.

In accordance with this object, one feature of the invention contemplates the provision in a machine for operating upon the marginal portion of a shoe sole having a sole 45 support and a tool comprising a carrier and a working element for operating upon the sole, which is actuated to give a rubbing pressure to the sole, of a heating block held in contact with the carrier, and means to uniformly heat the block to heat the tool by conduction.

In the preferred form of the invention the heating block is constructed with a com- 50 paratively large volume of good heat con-

ducting metal which is heated by an electric 55 resistance heating unit. The heating block is fixed on a bushing which guides the carrier, and is held directly in contact with the carrier, so that the heat is conducted directly to the tool.

60 The invention also includes certain features of construction and combinations of parts hereinafter described and pointed out in the appended claims.

The various features of the invention are 65 illustrated in the accompanying drawings, in which Figure 1 is a view in side elevation of the upper portion of an impression stitch burnishing machine of well-known construction; Fig. 2 is a view in vertical section 70 of the machine shown in Fig. 1; and Fig. 3 is a detail view showing the heating block in section and illustrating its connection on the machine head.

The impression stitch burnishing machine 75 illustrated in the drawings has substantially the same construction and operation of parts as the machine shown in the patent to Flynt, No. 845,939, dated March 5, 1907. This machine has a support 10 for the sole, and an 80 indenting and burnishing tool which comprises a working element 12 which is mounted upon a carrier or plunger 14. The plunger 14 is slidably mounted in the machine head 16, and is reciprocated to rub the 85 working element across the face of the sole, by means of a cam on the main driving shaft 18. The head 16 is rotatably mounted upon the shaft 18, and is yieldingly pressed by means of a spring 20 toward an abutment 90 screw 22. The spring 20 acts to clamp the sole between the burnishing tool and the support 10 during the indenting operation, so that the tool gives a rubbing pressure 95 upon the sole. The parts above described are the same as those shown in the patent above referred to, and reference is hereby made to said patent for a detailed description of the parts.

In order to heat the tool during the operation of the machine, a block having a comparatively large volume of metal is heated by means of an electrical resistance unit and held in contact with the tool carrier. The heating block 24 has a sleeve 26 100 which is arranged to fit over a flange 28 on a bushing 30 which is mounted in the machine head and acts as a guide for the 105

plunger 14. The block 24 is secured to the bushing 30 by means of a pair of set screws 32 which pass through the sleeve 26 and abut against the flange 28. An electric resistance heating unit 34 is placed in a chamber 36 formed in the block 24, and the unit is held in position by means of a pair of screws 38. The lower face of the block 24 is milled to closely fit over the tool carrier 14 to form a good heat conducting contact therewith, and the body of metal between the bottom of the chamber 36 and the face of the block which is in contact with the tool carrier is comparatively thin, so that the heat readily passes from the unit 34 into the tool carrier 14.

The electric resistance heating unit 34 is connected with a pair of leads 40 which have terminals in a junction box 42 secured on the machine frame. In order to hold the leads 40 from interfering with the work, they are passed through an insulating ring 44 which is secured in the machine head. Power for heating the unit 34 is led in through main conductors 46 which are connected with the leads 40 by means of the usual junction plug 50.

With the construction described above, the heating unit in the heating block may be quickly connected with electrical power, and the tool brought up to the required heat. Any desired temperature can be given to the tool by placing heating units of any required heat capacity in the heating block 24. The electrical heat is much more steady and uniform than any heat which has been used heretofore, and the heating block 24 is only heated slightly above the temperature which is required to heat the tool. In this manner a large supply of heat can be stored in the heating block, and the tool quickly heated to the desired temperature. The temperature of the block is not high enough to affect the temper of the tool, and there is no naked flame or heat sufficient to ignite the inks which are employed in treating the sole. The connection of the heating block upon the bushing which guides the tool carrier also operates to store heat in the bushing to thereby keep a uniform heat in the burnishing tool. If, however, heat is lost by conduction through the bushing to the machine head, the heating block may be insulated from the bushing 30 by means of the usual mica washers.

Although the invention has been described as embodied in an impression stitch burnishing machine, it is not limited to use in this machine, but may be employed in any type of machine for working upon the edges of soles in which a steady uniform heat is required.

Moreover, in its broader aspects, the invention is not restricted to the specific form 65 of tool and its mode of mounting and man-

ner of operation, it being evident that the advantages and benefits of the invention may be secured by the use of a tool, the working element and shank portion or carrier of which are materially modified in construction. In the claims, therefore, except as more specifically defined, the term "tool" is used in its generic sense to mean any form or type of tool and to include both the working element and its carrying or supporting member.

Having thus described my invention, what is claimed as new is:—

1. A machine for operating upon the marginal portions of shoe soles, having, in combination, a support for a sole, a tool comprising a carrier and a working element on said carrier for burnishing the edge of the sole, means to clamp the sole between the tool and the support, a heating block in contact with the carrier, means to uniformly heat the block, and mechanism to reciprocate the carrier back and forth across the face of the block to operate upon the sole. 70

2. A machine for operating upon the marginal portions of shoe soles having, in combination, a support for a sole, a tool comprising a carrier and a working element on said carrier for burnishing the edge of a sole, a bushing for guiding the carrier in its movements, a heating member fixed on said bushing and having a sliding contact with the carrier, means to heat said member, and mechanism operating upon the end of the carrier to rapidly reciprocate it through said bushing and across the face of the heating member in a direction transverse to the edge of the sole operated upon. 90

3. A machine for operating upon the marginal portions of shoe soles, having, in combination, a support for a sole, a tool comprising a carrier and a working element on said carrier for burnishing the edge of a sole, means to clamp the sole between the support and the tool, a bushing for guiding the carrier, a heating member fixed to the bushing and having a sliding contact with said carrier, an electrical resistance heating unit mounted in said member, means for supplying electrical energy to said unit, and mechanism to rapidly reciprocate the carrier back and forth across the face of the heating member while operating upon a sole. 105

4. A machine for operating upon shoes having, in combination, a tool comprising a carrier and a working element mounted thereon, a heating block in contact with said carrier, means for heating said block, means for moving said carrier across the contacting face of said block, and means for yieldingly moving the block toward the shoe and holding the tool in working engagement with a shoe. 120

5. A machine for operating upon shoe soles having, in combination, a tool compris- 130

ing a carrier and a working element mounted thereon, a bushing for guiding said carrier, means associated with said bushing and having a sliding engagement with said carrier for heating said tool by conduction, and means for reciprocating said tool in a direction transverse to the edge of the sole operated upon.

6. A shoe machine having, in combination, a support for a shoe, a tool for operating upon a shoe on said support, means for clamping the shoe between the tool and the support, a heated contact block in engagement with the tool, and means for reciprocating said tool across the engaging face of the contact block while operating upon the shoe.

7. A shoe machine having, in combination, a support for a shoe, a tool for operating upon the shoe on said support, means for

clamping the shoe between the support and the tool, means for rapidly reciprocating said tool, a relatively stationary bushing for guiding the tool, a heating member carried by said bushing and having a sliding engagement with said tool, and electrical means associated with said member for supplying heat thereto and thereby heating the tool by conduction.

8. A shoe machine having, in combination, a rapidly reciprocating tool for operating upon a shoe, movable means for supporting and guiding said tool, a heated member associated with said movable supporting and guiding means and having a sliding engagement with said reciprocating tool, and means for moving said movable supporting and guiding means to yieldingly hold the tool in working engagement with the shoe.

JOHN H. RIGBY.
